DESIGN FOR A PROJECTION VIEWING APPARATUS

Roy S. Hopkins, Rochester, N. Y., assignor to Eastman Kodak Company, Rochester, N. Y., a corporation of New Jersey

Application October 21, 1938, Serial No. 80,581

Term of patent 14 years

To all whom it may concern:

Be it known that I, Roy S. Hopkins, a citizen of the United States, residing at Rochester, in the county of Monroe and State of New York, have invented a new, original, and ornamental Design for a Projection Viewing Apparatus, of which the following is a specification, reference being had to the accompanying drawing, forming part thereof, and in which:

Fig. 1 is a perspective view and Fig. 2 is an end view of a projection viewing apparatus, showing my new design.

I claim:

The ornamental design for a projection viewing apparatus, as shown.

ROY S. HOPKINS.
